CLAIM

The ornamental design for a sunscreen packaging dispenser as shown and described.

DESCRIPTION

FIG. 1 is a top perspective view of the sunscreen packaging dispenser of the present invention showing my new design; FIG. 2 is a front view thereof, with the rear, left-side, and right-side views being identical to FIG. 2; FIG. 3 is a top view thereof; FIG. 4 is bottom view thereof; and, FIG. 5 is an exploded front view thereof. The broken lines in FIG. 5 depict environmental subject matter and form no part of the claimed design. The broken lines in FIG. 4 depict portion of the sunscreen packaging dispenser that form no part of the claimed design.
